BELT LOOP HOLDER

Edna M. Franklin, Oklahoma City, Okla.

Application May 22, 1952, Serial No. 289,354

1 Claim. (Cl. 2—236)

The present invention relates to means for attaching 15 belt loops to garment, particularly to ladies' dresses.

Belt loops now in common use on ladies' dresses are usually formed out of a string made up of chain-stitched thread. The ends of each string are bent into the side seam of a dress and are sewed in place as the seam is stitched together. This means that when it is desired to raise or lower the loops, a portion of each side seam must be ripped out to release the belt loop therein, and the seam must be resewed after the belt loop string has been moved to its new proper place.

The principal object of the present invention is to provide a new and novel means for attaching belt loop strings to the garment, the arrangement being such that the belt loop can be raised or lowered without ripping out any of the dress seams.

Another object is to produce a belt loop attaching means which may be originally installed upon a garment without ripping out any seam thereof.

A further object is to produce a belt loop fastener so designed that the loop may be removed with little trouble, and which can be removed and used on another garment if desired.

Yet another object is to produce an article which will be permanently positioned, and yet which will be substantially out of sight while in use.

Still another object is to produce an article of this class which is comparatively cheap to manufacture, and which may be installed without the expert services of a dressmaker.

Other objects will be apparent from the following description when taken in conjunction with the accompanying single sheet of drawings, wherein:

Figure 1 is a perspective view of the belt loop holder showing in dotted lines a portion of a blouse on which it is installed;

Figure 2 is a perspective view of the belt loop holder showing one end fastened, and the other end unfastened;

Figure 3 is a perspective view of the belt loop, showing an anchoring sleeve covering each end thereof, one sleeve being shown in a penetrating or inserting position, and the other sleeve being shown in its anchoring position;

Figure 4 is a perspective view showing a slightly different embodiment of holder than that shown in Figs. 1, 2 and 3; and

Figure 5 is a sectional view of a belt loop holder, showing the loop laced through the grommets therein, and showing one end of the string knotted, and the anchoring sleeve on the other end of the string.

Like characters of reference designate like parts in those figures of the drawings in which they occur.

In the drawings:

The referenced numeral 1 indicates, as a whole, a sheet of cloth which is folded longitudinally upon itself along a crease 2 to form two tab portions or flaps 3 and 4. The tab portion 3 is provided with two spaced male portions 5 of a conventional glove-snap fastener, and the tab por-

2

tion 4 is provided with two similarly spaced female portions 6 of a conventional glove-snap fastener. In installing the sheet 1 upon a dress the tab portion 3 is disposed flatly against the dress goods on the inner face thereof at 5 a point where it is desired that a belt loop be attached for use along the outer surface of the dress goods, and may be if desired sewed thereto. This installed arrangement leaves the tab portion 4 free to swing outwardly away from the tab 3 and the dress goods.

10 The referenced numeral 7 indicates, as a whole, a length of string or string-like element for forming the belt loop of the garment. Each end of the string 7 is inserted within and attached to a tubular anchoring element or fitting 8. Each anchoring element 8 has a point 9 whereby it can be pushed through the garment material and through the tab portion 3 of the sheet 1. As best shown in Fig. 3, the string 7 enters the tubate anchor 8 at a point intermediate the ends thereof. The remainder of the fitting has one side removed to provide a substantially hemitubate tail portion (Fig. 3). This arrangement allows for the element 8 to be bent at right angles to the string 7 and therefore prevent withdrawal of the anchored element.

In installing the belt loop string 7, the string is placed along the outer face of the garment material 11 and the points 9 and pressed through the garment material and through the tab 3 of the sheet 1. After the anchoring element or sleeve 8 has been placed through the two thicknesses of material, the element is bent at right angles to the string 7, and since the element 9 cannot be withdrawn 20 through the tab 3 of the garment material, the string is thereby anchored in place. After this is done the tab 4 is attached to the tab 3 by engaging the glove-snap fastening elements 6 over the fastening elements 5.

25 In Figure 4 is shown a slightly different embodiment of the belt loop fastener mechanism. In this embodiment the sheet 1 has been cut into two pieces, A and B. The sheet piece A has two tab portions 3-a and 4-a, and the sheet B has two tab portions 3-b and 4-b. These latter tab portions are provided with conventional male and female 30 glove-snap fastener elements 5-a and 6-a and 5-b and 6-b respectively.

35 As best seen in Fig. 5, the tab 3 may well be provided with two spaced grommets, each numbered 10, through which the string 7 is passed in the installation. This figure further shows that by knotting one end of the string 7, one of the anchoring sleeves 8 could be eliminated. Obviously the folded sheet 1 may well be used as a belt loop holder by placing it within a garment as described hereinabove, and inserting a string-like element through the 40 garment and the tab 3 and tying knots in the ends of the string-like element or tying the two ends together for holding the string-like belt loop forming element within the sheet 1.

45 Obviously the invention is susceptible to some change or alteration without defeating its practicability, and I therefore do not wish to be confined to the preferred embodiment shown in the drawings and described herein, further than I am limited by the scope of the appended 50 claim.

55 I claim:

50 In a means for anchoring a belt loop to a garment-forming fabric the combination with a string-like element having each end, respectively, secured within a pointed-ended tubate body adapted for transversely pivoting with 55 relation to said element, of: a pliant fabric folded upon itself forming two tab portions, whereby one of said tab portions may be flatly disposed on the inner surface of a garment-forming fabric, leaving the other tab portion free to swing toward and away from the first said tab portion; 60 and means for fastening said two tab portions together, whereby said tubate ends of said string-like element may

be thrust through said garment-forming fabric and said fastened tab portion in spaced-apart relation and disposed flatly thereagainst by pivoting said tubate ends and fastening said tab portions together, thereby forming a belt loop on the outer side of the garment-forming fabric.
